UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

YIELDABLE TRANSFERRER ARM FOR AUTOMATIC LOOMS.

Application filed July 19, 1924. Serial No. 727,077.

To all whom it may concern:

Be it known that I, ELBRIDGE R. HOLMES, a citizen of the United States, residing at Worcester, in the county of Worcester and 5 State of Massachusetts, have invented a new and useful Yieldable Transferrer Arm for Automatic Looms, of which the following is a specification.

This invention relates to improvements 10 in weft replenishing mechanism for looms and more particularly to the transferrer arm by means of which a full bobbin is moved into a shuttle carrying a depleted bobbin.

15 In the usual form of multi-color weft replenishing mechanism such, for instance, as that shown in Patent No. 1,030,748, the bobbins are moved from a plurality of compartments to a common discharge or transfer position. The transferrer arm is located 20 between inclined guides and moves toward the bobbin to be transferred as the lay approaches the forward limit of its motion. It is usual to have a solid part of the lay 25 engage a latch which is pivoted to the transferrer arm so that the latter is required to move as the lay advances. Occasionally a bobbin will not move entirely to transfer position before the transferrer begins to 30 descend and the bobbin will be caught between the transferrer arm and the guideway. Under these circumstances, with the lay moving and the transferrer held against motion, some part necessarily breaks and it 35 has been found in practice that the lower portion of the inside frame of the replenishing mechanism is the part which most frequently is ruptured.

It is the principal object of my present 40 invention to provide transfer mechanism constructed with a breakable portion which is sufficiently strong under all normal conditions to effect proper transfer but is weak enough to break when the parts are subjected to abnormal strain, the part to be 45 broken being readily replaceable and relatively inexpensive.

The replenishing mechanism of the type referred to must be restored to normal condition at the end of the forward stroke of the lay which would ordinarily result in a transfer. This is usually accomplished by means of two devices which form parts of the replenishing mechanism. One of these

devices is the usual shuttle feeler and the other is a transferrer latch which is lifted to connect the transferrer arm temporarily to the lay. The latch is lifted by a rod, the upper end of which is connected to the top shaft of the replenishing mechanism and 60 the lower end of which is looped under a cam face formed on the lower part of the latch. As the latch is moved forward, the cam face thereon depresses the rod to reset the top shaft. If any part of the transfer 65 mechanism breaks and the shuttle feeler be defective the replenishing mechanism will remain unset. It is a more particular object of my present invention to provide a transfer mechanism which will break when subjected to unusual strain but arranged so that the replenishing mechanism may be 70 reset even though the parts of the transferrer arm have been ruptured.

With these and other objects in view 75 which will appear as the description proceeds, my invention resides in the combination and arrangement of parts hereinafter described and set forth in the claims.

In the accompanying drawing, wherein I 80 have shown a convenient form of my invention,

Fig. 1 is a side elevation of a portion of the replenishing mechanism having my invention applied thereto, with the outside 85 plate removed for the sake of clearness.

Fig. 2 is a view similar to Fig. 1 but with the parts shown as they would appear when ruptured and after resetting the magazine,

Fig. 3 is a vertical section on line 3—3 90 of Fig. 1, and

Fig. 4 is a vertical section on line 4—4 of Fig. 2.

Referring to the drawing, it will be seen that I have provided a loom side 10 on which 95 is secured the frame 11 of a replenishing mechanism indicated at 12. A transferrer arm 13 is pivotally mounted on a fixed stud 14 and has a bobbin engaging heel 15 and a pair of depending arms 16 between which 100 extends a stud 17. The lay 18 is provided with a bunter 19 secured thereto and positioned for engagement with a transferrer latch 20 which is adjustably held to latch holder 21 by means of bolt 22. The replenishing mechanism is provided with a guide 23 which is positioned to receive bobbins 105 which may originate from compartments 24

of the replenishing mechanism. A rod 25 is connected at the upper end thereof with a lever (not shown) which is raised preparatory to transfer and the lower end of the rod 25 is looped under the latch 20 as indicated at 26 in Fig. 4. The lower end of the rod 25 is guided in any manner as by pins 27 which prevent forward motion of the rod as the latch is moved under action of the lay.

10 The matter thus far described is of the usual construction and for a more complete description thereof reference may be had to the aforesaid Patent No. 1,030,748.

15 My invention relates more particularly to the means for connecting the transfferer latch holder 21 to the stud 17 and in carrying out my invention I provide said holder with an upward extension 30 having formed thereon a semi-circular bearing 31 which together with a similar bearing 32 formed in a separate bearing block 33 forms the bearing for stud 17. The said block 33 is held to the extension 30 by means of a bolt 34 which is of light construction and serves to hold 20 the bearing portions 31 and 32 together.

25 In the normal operation of the replenishing mechanism the parts will be in the position shown in Fig. 1 and at the time of transfer the bobbin engaging heel 15 will descend as the lay 18 continues to advance, the bobbin sliding down guideway 23 into position to be engaged by the transfferer and moved into the shuttle. However, should the bobbin W be slow in moving to 30 transfer position due either to being oversize or to the improper releasing thereof the heel 15 will engage it and be held against further downward motion. At this time the lay, as it continues to move forward, will move the bunter 19, latch 20, and latch holder 21 but the block 33 will be held against forward movement by the stud 17 and the bolt 34 will break, permitting the parts to assume some such position as shown 35 in Fig. 2. The transfferer latch 20 is provided on the under surface thereof with a cam face 35 and the latch holder is provided with a surface 36 on the upper portion thereof which lies under the stud 17. As the 40 latch moves forward under influence of the lay and the rod 25 is in raised position the cam face 35 will engage the lower edge of the rod, the first effect of which will be to move face 36 against stud 17 after which further upward movement of the latch would be prevented and as the same moves forward the rod 25 will be moved downwardly to reset the replenishing mechanism.

45 From the foregoing it will be seen that I have provided a very simple construction by which abnormal strains incident to improper transfer may be relieved and that the movement of the parts is such that when the lower parts of the transfferer mechanism become ruptured the replenishing

mechanism will be properly set. I am aware that Patent No. 880,810 granted March 3, 1908 to Morell shows a yielding connection between the lay and the transfferer, but with such a device faulty transfers can occur repeatedly without the attendant being aware of the fact, whereas in my present construction the loom is stopped by the action of the filling stop motion (not shown) which will operate subsequently to the breaking of the bolt 34. Also, the patent to Morell fails to show any device for resetting the replenishing mechanism. The parts as presented herewith add very little to the cost of the transfferer and latch and permit the reassembly of a broken connection at slight expense.

50 Having thus described my invention it will be apparent that changes and modifications may be made therein by those skilled in the art without departing from the spirit and scope of the invention, and I do not wish to be limited to the details herein disclosed, but what I claim is:

1. In a weft replenishing mechanism for 55 looms, a lay, a pivoted transfferer arm, a latch, a support for the latch pivoted to and moving with the transfferer arm and movable to a position to be engaged by the lay, said pivotal connection being formed in part 95 by a breakable member sufficiently strong under normal conditions to effect transfer but weak enough to be broken under conditions of abnormal transfer to disconnect the latch from the transfferer arm to render 100 subsequent transfer impossible.

2. In a weft replenishing mechanism for 105 looms, a lay, a transfferer arm, a latch movable to engage the lay, a two part holder for the latch pivotally connected to and moving with the transfferer arm, and a breakable member holding said two parts of the latch holder together, said member being sufficiently strong to effect transfer 110 under normal conditions but being breakable under abnormal conditions to disconnect the latch from the transfferer to render subsequent transfer impossible.

3. In a weft replenishing mechanism for 115 looms, a lay, a transfferer arm, a stud carried by the transfferer arm, a latch engageable with the lay, a two part holder for the latch, the parts of said holder having pivotal contact with the stud, and a breakable member holding said parts together, said 120 member being sufficiently strong to effect transfer under normal conditions but weak enough to break under abnormal conditions to effect separation of the latch from the transfferer arm.

4. In a weft replenishing mechanism for 125 looms, a lay, transfferer mechanism including an arm, a yieldable connection between the lay and the transfferer arm to yield under abnormal conditions, and resetting 130

means for the replenishing mechanism positioned to be acted on by the transerrer mechanism to have a resetting movement after said connection has yielded.

5. 5. In a weft replenishing mechanism for looms, a transerrer arm, a lay, a latch connected to the arm, means when raised to lift the latch in the path of the lay and when lowered to reset the replenishing mechanism, connections between the transerrer arm and the latch sufficiently strong under normal conditions to effect transfer but weak enough under abnormal conditions to break, and means formed on the latch and operatively positioned with said first named means to lower said first named means after

the connection between the arm and the latch has been broken.

6. In a weft replenishing mechanism for looms, a lay, a transerrer arm, a latch, 20 a latch holder, a stud carried by the transerrer arm, means defining a pivotal connection between the latch holder and the stud, resetting means effective when depressed to reset the replenishing mechanism and a cam 25 face formed on the latch to engage said depressing means, the latch and latch holder lying between said stud and that portion of the resetting means engaged by said cam.

In testimony whereof I have hereunto affixed my signature.

ELBRIDGE R. HOLMES.
